UNITED STATES PATENT OFFICE

2,520,245

AIR JET PIN WHEEL

Anthony Indehar, St. Paul, Minn.

Application February 11, 1947, Serial No. 727,867

1 Claim. (Cl. 46—56)

1

This invention relates to new and useful improvements and structural refinements in toys, and the principal object of the invention is to provide a device of the character herein described, wherein a pin wheel may be caused to rotate by blowing into a tube-like handle on which the pin wheel is mounted.

A further object of the invention is to provide a toy wherein the handle, if desired, may be equipped with a whistle, the same being actuated concurrently with the rotation of the pin wheel.

Another object of the invention is to provide a toy which is of a highly entertaining character and which will not easily become damaged.

An additional object of the invention is to provide a toy which is simple in construction and which will readily lend itself to economical manufacture.

With the above more important objects in view, and such objects as may become apparent as this specification proceeds, the invention consists essentially of the arrangement and construction of parts as illustrated in the accompanying drawings, in which:

Figure 1 is an elevational view of the invention.

Figure 2 is a fragmentary, edge view thereof.

Figure 3 is a cross sectional view, taken substantially in the plane of the line 3—3 in Figure 1, and

Figure 4 is a perspective view of a modified embodiment of the invention.

Like characters of reference are used to designate like parts in the specification and throughout the several views.

Referring now to the accompanying drawings in detail, the invention consists of a toy designated generally by the reference character 10, the same embodying in its construction a tubular handle 11 closed at one end thereof as at 12 and provided at its remaining end with a sleeve-like mouthpiece 13.

A pin or rivet 14 extends transversely through the handle 11 adjacent the closed end 12, and a wheel 15 is rotatably mounted on the pin 14, as will be clearly apparent from the accompanying drawings.

The wheel 15 consists of a hub portion 16 adapted to receive the pin 14, an intermediate portion 17 and a peripheric flange 18. It will be noted that the intermediate portion 17 is ribbed to pro-

vide a plurality of spaced, convoluting vanes 19, as will be clearly apparent from the accompanying drawings.

The tube or handle 11 is also formed with a discharge opening 20 adjacent the closed end 12, and when the invention is placed in use, the mouthpiece 13 is simply inserted into the mouth and it will be found that by blowing into the handle 11, air will be impelled through the aperture or opening 20 against the vanes 19. In this manner, the wheel 15 will be caused to rotate and the amusing nature of the invention be clearly apparent.

Referring now to the modified embodiment of the invention illustrated in the accompanying Figure 4, the toy designated generally by the reference character 25 shown herein, embodies in its construction a tubular handle 26 carrying at one end thereof a rotatable pin wheel 27, the structure thereof being similar to the structure of the aforementioned handle 11 and the wheel 15. The free end of the handle 26 is, however, provided with a whistle 28, whereby the rotation of the wheel 27 will be accompanied by the whistling sound.

It will be also noted that if desired, the peripheric flange 29 or the wheel 27 may be formed with a plurality of apertures or openings 30, each of which communicates with one of the spaces 31 existing between the adjacent ribs or vanes 32.

When the wheel 27 is in rotation, the apertures or openings 30 will function as convenient outlets for the air impelled against the vanes, as will be clearly understood.

It is believed that the advantages and use of the invention will be clearly understood from the foregoing disclosure and accordingly, further description thereof at this point is considered unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

In an air operated toy, a rotor disc having a hub portion and a peripheral flange, an inter-

mediate portion of said disc being imperforate and provided with convoluting ribs defining therebetween a series of channels, said channels having pinched bottom walls and progressively increasing in width from said hub portion to said flange, said flange being formed with air outlet apertures each communicating with one of said channels, said apertures being of substantially lesser dimensions than the width of the outer ends of said channels.
